ATTORNEY

UNITED STATES PATENT OFFICE.

JAMES M. BEAN, OF WATERTOWN, MASSACHUSETTS.

CAN AND CASE.

SPECIFICATION forming part of Letters Patent No. 298,338, dated May 13, 1884.

Application filed February 29, 1884. (No model.)

To all whom it may concern:

Be it known that I, JAMES M. BEAN, of Watertown, in the county of Middlesex and State of Massachusetts, have invented a new and useful Improvement in Cans and Cases therefor, of which the following is a specification.

The objects of my invention are to provide a cheap, simple, convenient, and durable tilting can and case for kerosene-oil and other liquids, which case will securely protect the can from injury in shipping, and also serve as a support for the can when elevated therein, to enable it to be tilted or tipped or swung upon journals or pivots provided upon opposite sides of the can, and adapted to have a bearing upon the top edge of the case when partially withdrawn from the same, so as to permit the contents of such can to be poured from the same through a spout connecting with the interior of the can and attached to the top of the same, as hereinafter more fully described, and set forth in the claims.

Figure 1 represents a perspective view of a can and case constructed according to my invention, and connected together ready for transportation or storage. Fig. 2 represents a similar view of the can elevated upon the case and tipped so as to remove the contents. Fig. 3 represents a vertical section through the swinging nozzle or spout and a portion of the can-top to which it is secured. Fig. 4 represents a vertical section through a portion of one side of the can and can-guard secured thereto.

35 A represents a square or rectangular metal can, constructed of tin, and having secured to opposite sides thereof, by solder or otherwise, suitable pivots, B, which slide down within vertical grooves formed within the opposite ends C of the case. When the said can A is placed therein, as shown Fig. 1, and when raised upward and partially removed therefrom and the said pivots B placed in slight notches formed in the upper ends of the said 45 projecting ends C of the case, as shown in Fig. 2, it is free to be tipped or tilted so as to pour through the faucet or swinging spout D the contents of the said can A. This swinging spout is adapted to be opened and closed by 50 having a slight rotary motion imparted to it, whereby the spout D is carried around horizontally about one-fourth of a revolution, which

opens or closes the passage through the spout connecting with the vertical cylindric case E, which rotates with the interior packing or 55 cork, G, which is provided with a central vertical tube, F, and a horizontal opening arranged to coincide with the opening through the spout D, and the case E, which has a bearing at its lower end upon the disk or plate J, soldered 60 upon the top of the can around an opening provided therein, and at its upper end upon the under face of the cap-plate K, which is soldered to the upper end of the short vertical tube F, as shown in Fig. 3.

The can is provided on its upper end with a filling-hole covered by a screw-cap, L, and a handle, M, which are protected from injury in transportation by the thick bars N, extending across the top of the can at each side of the 70 screw-cap, handle, and swinging spout, and are secured at their opposite ends to the case-pieces P, which are secured to the front and rear sides of the can, at their upper and lower edges, by a strip of tin, R, nailed or secured to 75 the inward faces of the said pieces P, and projecting below the lower ends thereof when the said bars N and case portions P are placed over and upon the top of the said can A and the tin strips R soldered to the sides of the can, as 80 shown in Fig. 4.

It will be seen and understood that when the said can A is placed within the case, as shown in Fig. 1, the said portions P fit within the ends C of the case and bear at their lower 85 ends against the upper ends of the lower or short back and front portions, S, of the case, and may be connected thereto by a suitable eye and hasp attached to each side, as shown; or, if desired, the hasps may be attached to the 90 tops of the said cross-bars N, and the screw-eyes inserted into the upper ends of the end-pieces, C, of the case or cleats T, and thereby temporarily secure, attach, or connect the can with the said case in a convenient manner. The 95 said ends C of the case have secured to their upper end portions cleats T, which extend across the same from edge to edge, and thereby strengthen the same, so as to prevent splitting or breaking in handling and transporting the same. 100

Having thus described my invention, what I claim is—

1. The can A, having a faucet consisting of the disk J, attached to the can, a cap, K, tube

F, secured to the cap and to the disk, an outer cylindric case, F, having a spout, D, secured thereto, and a packing, G, substantially as described.

5 2. The can A, provided on its upper end with the bars N and on its opposite sides with the case-pieces P, secured to the bars N, and secured to the can by the metal strips R, substantially as described.

10 3. The combination of the can A, provided with the top bars, N, and on its opposite sides

with the case-pieces P, secured to the bars N, and secured to the can by metal strips R, with the case end pieces, C, provided with the cross-cleats T and short back and front portions, S, 15 adapted to be connected together and disconnected, substantially in the manner described, as and for the purposes set forth.

JAMES M. BEAN.
